UNITED STATES PATENT OFFICE.

THOMAS F. COONEY, OF WEST HAVEN, CONNECTICUT.

DESIGN FOR A JUICE EXTRACTOR.

Application filed May 1, 1928. Serial No. 26,523. Term of patent 14 years.

To all whom it may concern:

Be it known that I, THOMAS F. COONEY, a citizen of the United States, residing at West Haven, county of New Haven, and State of Connecticut, have invented a new, original, and ornamental Design for a Juice Extractor, of which the following is a specification, reference being had to the accompanying drawing, forming part thereof.

I claim:—

The ornamental design for a juice extractor, substantially as shown.

THOMAS F. COONEY.
